DESIGN FOR A CASE FOR MECHANIZED RAZORS

Neil Holsclaw, Chicago, Ill.

Application May 2, 1941, Serial No. 100,740

Term of patent 14 years

To all whom it may concern:

Be it known that I, Neil Holsclaw, a citizen of the United States, residing at Chicago, in the county of Cook and State of Illinois, have invented a new, original, and ornamental Design for a Case for Mechanized Razors, of which the following is a specification, reference being had to the accompanying drawing, forming part thereof.

Figure 1 is a perspective view of a case for mechanized razors, showing my new design.

Fig. 2 is a side view thereof.

Fig. 3 is an edge view thereof.

Fig. 4 is a top view thereof.

I claim:

The ornamental design for a case for mechanized razors, as shown.

NEIL HOLSCLOW.
